COMBINED SHOVEL, SCRAPER AND BRUSH, OR THE LIKE

Jon W. Hauser, St. Charles, Ill., assignor to National Brush Company, Aurora, Ill., a corporation of Illinois

Filed Sept. 29, 1961, Ser. No. 66,902

Term of patent 3½ years

(Cl. D9—6)

FIG. 1 is a reduced top plan view of a combined shovel, scraper and brush, or the like, showing my new design;

FIG. 2 is a fragmentary side elevational view of the scraper end thereof;

FIG. 3 is an elevational view taken from the open end of the scraper element;

FIG. 4 is a sectional view taken along the line 4—4; and

FIG. 5 is a fragmentary bottom plan view thereof.

The major portion of the shovel and brush are broken away in FIGS. 2 and 5 for purposes of illustration only.

The dominant features of my new design reside in the portions shown in full lines.

I claim:

The ornamental design for a combined shovel, scraper and brush or the like, as shown and described.
